The ornamental design for a horseshoe cuff, as shown and
described.

DESCRIPTION

FIG. 1 is a top front perspective view of the horseshoe cuff
mounted to a horseshoe pad;

FIG. 2 is a left side elevation view of the horseshoe cuff
mounted to a horseshoe pad;

FIG. 3 is a rear elevation view of the horseshoe cuff;

FIG. 4 is a front elevation view of the horseshoe cuff;

FIG. 5 is a bottom plan view of the horseshoe cuff;

FIG. 6 is a top plan view of the horseshoe cuff;

FIG. 7 is a left side elevation view of the horseshoe cuff;

FIG. 8 is a right side elevation view of the horseshoe cuff;

FIG. 9 is a top front perspective view of the horseshoe cuff;

FIG. 10 is a top rear perspective view of the horseshoe cuff;

FIG. 11 is a bottom front perspective view of the horseshoe
cuff; and,

FIG. 12 is a bottom rear perspective view of the horseshoe
cuff.

In all of the views, the equal-length broken lines on the
horseshoe cuff depict portions thereof and form no part of
the claim. In FIGS. 1 and 2, the equal-length broken lines
showing a horseshoe pad depict environmental structure and
form no part of the claim. All broken lines form no part of
the claimed design.
